UNITED STATES PATENT OFFICE.

MORRIS BERKOWITZ, OF BROOKLYN, NEW YORK, ASSIGNOR TO EXCELITE FIXTURE CORPORATION, OF NEW YORK, N. Y., A CORPORATION OF NEW YORK.

DESIGN FOR A BACK PLATE FOR A LIGHTING FIXTURE.

Application filed December 11, 1924. Serial No. 11,668. Term of patent 3½ years.

To all whom it may concern:

Be it known that I, MORRIS BERKOWITZ, a citizen of the United States, residing in the borough of Brooklyn, Kings County, city and State of New York, have invented a new, original, and ornamental Design for a Back Plate for a Lighting Fixture, of which the following is a specification, reference being had to the accompanying drawing, forming a part thereof.

Fig. 1 is a plan view merely, and Fig. 2 is a side elevation, of a back plate for a lighting fixture showing my new design.

I claim:

The ornamental design for a back plate for a lighting fixture, as shown.

MORRIS BERKOWITZ.
